(57) **CLAIM**

The ornamental design for a ring sizing device, as shown and described.

DESCRIPTION

FIG. 1 is a perspective view of a first embodiment of a ring sizing device, showing our new design from the front, top, and one side;

FIG. 2 is a perspective view thereof, shown from the back, bottom, and the side opposite that shown in FIG. 1;

FIG. 3 is a side elevation view thereof;

FIG. 4 is a perspective view of a second embodiment of the ring sizing device, showing our new design from the front, top, and one side;

FIG. 5 is a perspective view thereof, shown from the back, bottom, and the side opposite that shown in FIG. 4;

FIG. 6 is a side elevation view thereof;

FIG. 7 is a perspective view of a third embodiment of the ring sizing device, showing our new design from the front, top, and one side;

FIG. 8 is a perspective view thereof, shown from the back, bottom, and the side opposite that shown in FIG. 7; and,

FIG. 9 is a side elevation view thereof.
